[57] **CLAIM**

The ornamental design for a display box, substantially as shown and described.

DESCRIPTION

FIG. 1 is a perspective view of a display box showing my new design;

FIG. 2 is a top plan view;

FIG. 3 is an end elevational view of the opposite end being a mirror image thereof;

FIG. 4 is a front elevational view;

FIG. 5 is a rear elevational view;

FIG. 6 is a bottom plan view thereof.

The interior surfaces of all four upstanding walls are mirrored.
